UNITED STATES PATENT OFFICE.

ANDREW J. FAIR, OF WALNUT COVE, NORTH CAROLINA.

MANTEL.

SPECIFICATION forming part of Letters Patent No. 595,052, dated December 7, 1897.

Application filed February 8, 1897. Serial No. 622,560. (No model.)

To all whom it may concern:

Be it known that I, ANDREW J. FAIR, a citizen of the United States, residing at Walnut Cove, in the county of Stokes, State of North Carolina, have invented certain new and useful Improvements in Mantels, of which the following is a specification, reference being had therein to the accompanying drawings.

This invention relates to certain new and useful improvements in mantels; and it has for its object, among others, to provide a mantel which shall be capable of serving a useful purpose in addition to its ordinary function as an ornament.

15 It is a well-known fact that a mantel is a "catchall" for all sorts of things, which render it untidy in appearance. This is because of the fact that there is no receptacle handy into which the articles can be placed where 20 they will not only be out of the way, but protected from the dust and dirt which naturally accumulate about the mantel. I provide the mantel with a drawer or a number of drawers, which add to the appearance of the 25 mantel, and in addition to these drawers I provide a secret chamber or receptacle where valuables may be placed where they will be beyond the reach of burglars or other maliciously-inclined persons. I may further provide 30 a secret box or receptacle that shall be locked against opening until one of the drawers is entirely pulled out, when the locking mechanism is released.

Other objects and advantages of the invention will hereinafter appear, and the novel features thereof will be specifically defined by the appended claims.

The invention is clearly illustrated in the accompanying drawings, which, with the letters of reference marked thereon, form a part of this specification, and in which—

Figure 1 is a front elevation of my improved mantel with a portion broken away and parts in section. Fig. 2 is a vertical section on the 45 line 2 2 of Fig. 1. Fig. 3 is a perspective detail, on a larger scale, of the locking-bolt and its spring removed.

Like letters of reference indicate like parts throughout the different views.

50 Referring now to the details of the drawings by letter, A designates the mantel, which may be of any preferred design, in this in-

stance shown as of that class known as "cabinet" mantels.

B are the vertical pillars or supports, and 55 C the projecting ledge or shelf. Beneath this shelf or ledge is a sliding drawer D, which may be of any desired length and adapted to slide in the space E and is supported upon the horizontal support F.

60 Upon each side of the mantel are the secret compartments G, arranged to slide within the space H, provided in the vertical pillars or supports, as shown. These compartments or sliding boxes may be of any desired outward 65 configuration, being designed to have the appearance of ornaments only. They are locked in the following manner: At the right of Fig. 1 I have shown a portion broken away in order to show the construction and arrangement 70 of the locking means. The device at the opposite side is the same. A description of but one therefore is necessary.

75 I is a bolt arranged to slide in the vertical walls or partitions J and J' between the drawer G and the drawer D, as seen clearly in Fig. 1. It is arranged near the front of the mantel, as indicated in Fig. 2, so that the drawer D must be drawn almost, if not entirely, out. This bolt has a beveled end, as 80 seen at i in Fig. 3. Its other end is adapted to engage an opening in the adjacent side of the sliding box G, as shown in Fig. 1. Around this bolt is a spring K, which engages a stop or pin k thereon, as seen best in Fig. 3. The 85 tendency of this spring is to force the bolt toward the drawer D. The bolt is arranged with the bevel toward the front of the mantel.

80 The operation will be readily understood. While the drawer D is in, so that the end of 90 the bolt will engage the side wall thereof, the bolt will be held in the opening in the side of the box G, as seen in Fig. 1, and the box cannot be withdrawn. It should be made to fit tightly against the adjacent portion of the 95 pillar, so as to guard against any disclosure of the fact that this part is designed to be withdrawn. When it is desired to remove the box G, the drawer D is withdrawn entirely or to such an extent that the rear end 100 thereof will pass the bolt, when the spring will force the bolt to the space occupied by the drawer and withdraw its other end from the opening in the side wall of the box G,

when the latter will be free to be pulled out wholly or in part, as may be desired. The spring holds the bolt in this position. After the box G is replaced the drawer D is pushed 5 in, and as it moves inward the beveled end of the bolt will be engaged thereby and the bolt forced outward and its outer end engaged in the opening in the side wall of the box G and the latter again locked against removal.

10 L is the upper shelf. Beneath the same are the drawers M, of any desired number. They are mounted to slide above the horizontal plate or portion N, which is arranged at a distance below the shelf considerably greater than the height of the drawer, as seen best 15 in Fig. 2, so as to leave a space O above the top of the drawer.

P is a board or plate extending the whole length of the space within which the drawers 20 are arranged. Its rear edge is beveled, as seen at p, and engages in a correspondingly-shaped groove in the rear wall of the mantel, as seen in Fig. 2. Its front edge is designed to be supported upon one or more of the drawers, 25 the construction being such that the board P cannot be removed until all of the drawers are removed. The board P is provided at its front edge with the ledge P', which prevents articles slipping from off the board when the 30 board is tilted downwardly to remove it from the mantel. When it is desired to place articles upon the board, they are laid thereon while the board is in an inclined position and the board raised by hand while one or more 35 of the drawers are being inserted. As soon as the drawer is placed in position the board will be supported thereon, so that the other drawers may be slid in place beneath the board. It will thus be seen that I provide a

secret compartment above the drawers which 40 will not be disclosed by the withdrawal of any one or more of the drawers.

Modifications in detail may be resorted to without departing from the spirit of the invention or sacrificing any of its advantages. 45

What is claimed as new is—

1. The combination with a mantel having a sliding drawer, of a removable portion forming a secret compartment, and means operated by the drawer for locking the compartment in position until the drawer is removed, substantially as specified. 50

2. The combination with the mantel and a sliding drawer, of a sliding receptacle located parallel therewith, a spring-actuated bolt 55 mounted to slide between the drawer and receptacle and to engage said drawer to automatically lock the receptacle until the drawer is withdrawn, substantially as specified.

3. The combination with a mantel and a series of sliding drawers, of a board above said drawers supported and held in position thereby and prevented from removal until all of the drawers are removed, substantially as specified. 60

4. The combination with a mantel and a series of sliding drawers therein, of a board adapted to be supported by said drawers and having its rear edge beveled and fitted in a corresponding groove in the rear wall, substantially as shown and described. 70

In testimony whereof I affix my signature in presence of two witnesses.

ANDREW J. FAIR.
